PISTON

Adolph L. Nelson, Detroit, Mich., assignor to
Bohn Aluminum & Brass Corporation, Detroit,
Mich., a corporation of Michigan

Original application June 2, 1934, Serial No.
728,663. Divided and this application March
24, 1937, Serial No. 132,681

2 Claims. (Cl. 309—13)

The present invention relates to an improved piston, and particularly to a light-weight piston adapted for use in internal combustion engines.

The invention provides a piston in which the 5 piston skirt is formed with a vertical slot and with a part that extends across one end of the slot and arranged to prevent spreading of the slot when a lathe or grinder center is inserted in the open end of the piston and to permit inward yielding of the skirt when pressure is created between the skirt and the cylinder in which the piston is operated.

This application is a division of my application Serial No. 728,663, filed June 2, 1934.

15 While preferred forms of the invention are disclosed herein for purposes of illustration, various changes may be made in the structure without departing from the spirit of the invention.

In the drawing:

20 Figure 1 is a side elevation of a piston embodying the invention.

Figures 2 and 3 are views similar to Figure 1 but showing modified forms of the invention.

The invention can be applied to any preferred 25 type of piston, and in the species of Figure 1 it is shown applied to a piston of the type illustrated in Nelson Patent No. 1,830,172 in which the expansion of the skirt is controlled by steel struts.

In these figures the piston includes the head 30 10, a lower ring 11 and a thrust face 12 which extends upwardly from the lower ring.

The invention is particularly adapted for use 35 on pistons formed of light-weight material, such as aluminum alloy. Pistons formed of these materials usually have a higher rate of thermal expansion than the cylinders in which they are used and they should be constructed so they will not slap when cold nor seize when hot. It is a common practice to provide such pistons with a vertical slot which permits the skirt to yield circumferentially as it expands into contact with the cylinder wall. One drawback in the use of such vertical slots is that if the slotted piston is placed on centers for a finishing operation, such 40 as grinding or boring the piston pin holes, the skirt spreads and is therefore in a distorted condition during the finishing operation.

According to the present invention a restrictor 50 part extends across at least one end of the slot, the restrictor part being arranged to prevent outward yielding but to permit narrowing of the slot under pressure.

In the preferred construction illustrated in 55 Figure 1 the lower ring 11 continues uninterrupted around the circumference of the skirt,

and the inner wall of the ring 11 provides a continuous contour. A slot 13 extends vertically through thrust face 12 and forms two separated wings 14 and 15. The lower end of this slot is circuitously arranged so as to form a hook 16 5 attached to wing 14 and hook 17 attached to wing 15. The inner faces of these two hooks engage each other as illustrated to prevent spreading of the lower end of the skirt, but extra clearance is provided as shown to permit movement of 10 the wings 14 and 15 toward each other to narrow the slot 13.

When a piston constructed in this manner is placed on lathe or machine centers, one center 15 engages the head of the piston and a tapered center is pressed inside the lower open end of the piston. This tapered center would, in the absence of the restrictor, spread the slot 13 and enlarge the lower end of the skirt, thus interfering with accurate finishing of the piston. But the 20 presence of the restrictor prevents any such spreading of slot 13.

On the other hand, the piston is yielding so far as concerns the cylinder in which it is later 25 assembled. Whenever the cylinder exerts pressure on the skirt of the piston, as when a rise in temperature causes the piston to expand faster than the cylinder, the restrictor does not interfere with the closing-in or narrowing of the slot 13.

In Figure 2 the restrictor is a ring 18 that has a snug fit with the sides of a groove. The ends of 30 the ring overlap and have hooks 19 and 20 that cooperate in a manner similar to the hooks of Figure 1.

The restrictor 21 of Figure 3 is a member that lies in a groove and is flush with the outer face of the skirt. The enlarged heads 22 engage in recesses in the skirt that provide clearance beyond the ends of the heads 22 to permit the skirt 40 to yield inwardly.

Any suitable material, for example steel, can be used for the restrictors.

I claim:

1. A piston comprising a head, a skirt with a 45 slot extending vertically therein and forming two separated wings, a hook member formed on each of said wings, said hook members being interengaged to prevent spreading of the slot when a lathe center is placed within the open end of the 50 piston, the skirt being provided with clearance which permits closing in of the slot when pressure is created between the skirt and the cylinder in which the piston is operated.

2. A piston comprising a head, a skirt with a 55

slot extending vertically therein, the lower end of the slot being circuitously arranged to provide two separated wings, each wing provided with a hook member, said hook members being inter-engaged to prevent spreading of the slot when a lathe center is placed within the open end of the

piston, the skirt being provided with clearance which permits closing in of the slot when pressure is created between the skirt and the cylinder in which the piston is operated.

ADOLPH L. NELSON.
